CARBURETOR

Eugene Rivoche, Washington, D. C.

Application April 1, 1948, Serial No. 18,439

16 Claims. (Cl. 261—40)

1

This invention pertains to a metering device and, more particularly, to carburetors for regulating the supply of fuel to internal combustion engines and the like.

Carburetors which are now in commercial use today utilize a plurality of jets of fixed capacity for permitting the passage of fuel therethrough, and a great majority of carburetors utilize a float chamber for maintaining a liquid level in an attempt to attain the proper fuel supply. 5 Difficulty has been encountered with the present day carburetor in that it tends to starve at high speed and can only supply fuel in accordance with the capacity of the fixed jets. One of the jets is utilized for starting, and the other, or both, for operation. There can be no change in the jets without taking down the carburetor and rendering the motor inoperative. In addition, such jets are apt to become dirty and there can be no regulation of the fuel supply therethrough without rendering the motor inoperative for a period of time.

Again some motor vehicles utilize one type of fuel for starting and another type of fuel for operation after starting has been effected and the engine warmed up. Such operation is generally effected by a plurality of carburetors. Where a single, usual carburetor is used it is necessary to drain (or use up) the fuel retained therein in order that starting fuel may be used. In the carburetors using the plurality of fixed jets, they are of different size and it is usual to use the large jet for starting because it is desired to supply a relatively large quantity of fuel so that the mixture of fuel and air will be such as to present an explosive mixture to the ignition device. Thus after starting and after the engine is warm, too great a quantity of fuel is supplied as there is no way to adjust the fixed jet.

However, in starting an engine it is cranked relatively slowly and the developed suction is, therefore small, so that it is difficult to supply a sufficient quantity of explosive mixture to the ignition device, and thus the starting motor and consequently the battery is called upon to rotate the crank shaft a number of times, which is a drain on the battery, and if the weather is cold the lubricating oil is more viscous, and difficulty is encountered in turning over the engine, which increases the difficulty of supplying the necessary explosive mixture for starting. Even after the engine is started, it is not economical, because then the large jet permits the engine to draw in a too great quantity of fuel in proportion to the

2

quantity of air so that a non-explosive mixture reaches the engine and flooding may occur. The starting difficulty can be alleviated somewhat by increasing the idling speed of the motor, but this is undesirable as it is uneconomical both from a standpoint of fuel consumption and wear and tear on the engine parts.

Again, in supplying too much fuel, there is a danger that an unburned part of the fuel will be expelled through the exhaust, or the unburned part of the fuel, being of a seeking nature, will find its way into the lubricating oil, diluting it and thereby destroying its effectiveness. This is further dangerous from a standpoint of wear and tear on the engine, because fuel, such as gasoline, is not a lubricant but is an abrasive. There are other instances in motor vehicles where it is desirable that for a particular zone such as city use, that a governor be used to prevent speeding, but for the most part these governors are unsatisfactory and, as a matter of fact, are dangerous as they do not permit rapid enough acceleration to their top limit of speed. Additionally such governors are undesirable because they do not permit an increase of speed beyond the set speed after the restricted speed zone has been left, because such governors cannot be adjusted without rendering the vehicle temporarily inoperative.

It is, therefore, an object of this invention to provide a carburetor provided with one or more adjustable jets.

Another object of the invention is to provide the carburetor for an internal combustion engine wherein there can only be a full synchronization in the mixture of air and fuel, in desired and easily adjustable proportions of air and fuel.

Another object of the invention is to provide a carbureting or metering device for an internal combustion engine wherein the carburetor acts not only as a carburetor, but also may be utilized as a mixer of fuels of different character.

Another object of the invention is to provide a carburetor for an internal combustion engine wherein a selected number of fuels may be used and the mixing thereof may be independent, both as to kind and quantity, one from the other.

Another object of the invention is to provide a carburetor for an internal combustion engine which operates under pressure and not only by aspiration.

Another object of the invention is to provide a carburetor which does not utilize a float, thus there is no reservoir of liquid adjacent the engine which could be ignited accidentally.

Another object of the invention is to provide a carburetor wherein the adjustment thereof can be effected while the internal combustion engine with which it is associated is in operation.

Another object of the invention is to provide a carburetor which may be adjusted at any time permitting adjustments for differences in temperature, differences in pressure, or differences in grade of fuel, all such adjustments being possible while the engine is in operation.

Another object of the invention is to provide a carburetor for an internal combustion engine which permits an easy adjustment and quick control of fuel consumption, whereby the internal combustion engine associated therewith can be operated as economically and efficiently as possible, and wherein the utmost performance can be attained, all such adjustments being possible while the engine is in operation.

Another object of the invention is to provide a carburetor which is positive of operation whereby it causes the engine with which it is associated to start immediately, whether the temperature is low or not, and regardless of the pressure with which the fuel is supplied or the aspiration of the engine and one wherein there is no dependence upon fuel level, and wherein there is always a proper mixture of air and fuel.

Another object of the invention is to provide a carburetor wherein the fire hazard is eliminated as no pool of fuel is carried as in the usual type of float carburetor.

Another object of the invention is to provide an inexpensive, easily operated, adjusted and repaired carbureting device for an internal combustion engine which will operate in any position of such device.

Another object of the invention is to provide a carbureting device for an internal combustion engine which is so constructed and arranged that overly large quantities of fuel cannot be supplied to the engine so there can be no flooding of the engine, nor can there be any vapor lock, and there is no danger that the unburned part of the fuel will mix with the lubricating oil or be dangerously expelled from the exhaust.

Another object of the invention is to provide a carburetor which is so constructed and arranged that it is self-cleaning, yet is easily regulated even while the engine is in operation.

Another object of the invention is to provide a carburetor for an internal combustion engine wherein a jet, or a plurality of jets, is provided which can be so adjusted as to provide, in effect, an infinite number of selected sized jets.

Another object of the invention is to provide a carburetor which is so constructed and arranged that a plurality of different fuels may be mixed in the carburetor for the supply to an internal combustion engine, the amount of such fuels being selectively variable.

Another object of the invention is to provide a carburetor wherein not only the supply of fuel can be varied during operation of the engine, but the richness and composition of the fuel-air mixture can be varied.

Another object of the invention is to provide a carburetor so constructed and arranged that it is readily interchangeable with engines of different size within a reasonable range, of course, the only substantial essential being one of adjustment.

With these and various other objects in view, the invention consists of certain novel features of construction and operation as will be more

fully described and particularly pointed out in the specification, drawings and claims appended hereto.

In the drawings which illustrate embodiments of the device and wherein like reference characters are used to designate like parts—

Figure 1 is an elevation, partly in section, showing a form of carburetor embodying the invention;

Figure 2 is a plan view, partly in section, of the carburetor illustrated in Figure 1, the section being taken substantially at right angles to that shown in Figure 1, i. e. in the plane as indicated by the line 2—2 of Figure 1;

Figure 3 is an enlarged sectional plan of one form of jet or injection device used in the carburetor, showing it associated with the mixing chamber of the device;

Figure 4 is a fragmentary elevation showing the injection end of the injection device illustrated in Figure 3;

Figure 5 is a fragmentary elevation of the inner adjustable injection tube for adjusting the carburetor for idling;

Figure 6 is an enlarged sectional plan of a modified form of jet or injection device used in the carburetor, showing it associated with the mixing chamber of the device;

Figure 7 is a transverse, sectional elevation through certain of the ports of the injection device illustrated in Figure 6, showing the relative position of the ports for idling of an internal combustion engine;

Figure 8 is a transverse sectional elevation corresponding to Figure 7, but showing the relative position of the ports when the governor port has been adjusted from the lower supply position shown in Figure 7 to a higher or greater capacity position;

Figure 9 is a transverse sectional elevation corresponding to Figure 8 but showing the outer ports having been moved to a position of accelerating an internal combustion engine;

Figures 10, 11 and 12 are diagrammatic, fragmentary, sectional elevations showing different arrangements of injection devices with a mixing chamber; and

Figure 13 is a diagrammatic sectional elevation showing a carburetor utilizing two jets, but arranged to supply more than two types of fuels to the mixing chamber.

The carburetors illustrated comprise a stationary casing 20, having a mixture outlet passage 22, and the securing flange 24 for connecting the casing 20 to the inlet manifold 26 of an internal combustion engine (not shown), passage 22 communicating with manifold inlet passage 28. Casing 20 is also provided with an intake passage 30, communicating with a source of air, as the atmosphere, through air filter (cleaner) 32.

Casing 20 is provided with an axial cylindrical bore 34, shown with the axis normal to passages 22 and 30, and the ends of said bore are closed by closure plates 36 and 38 rotatably mounted in said casing. Closure plates 36 and 38 are fixedly connected together by means of the cylindrical sleeve or tube 40 which is rotatably mounted in the bore 34, said tube 40 having oppositely disposed openings 42 and 44 communicating with passages 30 and 22, respectively. Rotation of tube 40 serves to regulate the extent of communication between the air filter 32 and the mixing chamber 46, formed in casing 20, tube 40 and between closures 36 and 38; and between the mixing chamber 46 and inlet manifold 26, as will be

more particularly hereinafter described. Thus the ported sleeve 40 forms a rotary valve with passages 22 and 30.

Referring now, more particularly, to the modification illustrated in Figures 1 to 5 and 7 to 9 (Figures 4, 5, 7 to 9 being equally applicable to the modification shown in Figure 6), oppositely disposed injection devices 48 and 50 extend through closures 36 and 38, respectively, the devices being preferably similar in construction, and are so disposed that the nozzles or nozzle ends 52 extend into the mixing chamber 46.

The outer or first injection member 54 of devices 48 and 50, is fixed in its respective closure 36 or 38, so that member 54 and its nozzle 52 turns with the sleeve 40. Member 54 is threaded adjacent its outer end for reception of the nut 56, the rear wall 58 of said nut terminating adjacent the inner or second injection member 60, and being adapted to engage slidable spring seat 62 encircling injection member 60. One end of spring 64 is seated on seat 62, the opposite end being seated on fixed seat 66 provided on said member 60.

Movement of nut 56 on the threaded end of member 60 varies the compression of spring 64, thereby urging the outer, tapered nozzle end 68 of member 60 into engagement with the inner, correspondingly tapered nozzle end 52 of member 54, with selected degrees of firmness.

Nozzle end 68 is provided with a port 70, shown frusto-conical in shape (though any desired shape may be used), the size of the port varying according to the size of the engine to be operated (amount of fuel to pass through the port), and according to the pressure to be used to supply the fuel to the engine. The larger the supply pressure, the smaller port 70 may be, and the more quick opening said port may be made.

Nozzles 52 are open at the ends in the mixing chamber 46 and each opening or port 72 is provided with a biased or inclined notched end 74, the angularity (steepness) of the incline depending upon the speed desired in opening port 70, the depth of the notch 76 being preferably sufficient to permit the members 60 and 54 to be so relatively positioned that port 70 is entirely open. Thus it may be said that the larger the engine or the lesser the supply pressure, the steeper the incline of opening 72 may be.

Each member 60 is provided with lever 76 fixedly secured thereto as at 80 and suitably connected as at 82 with the rotatable knob 84, said knob being provided with pointer 86, movable over calibrated dial 88 conveniently located to the operator of the engine with which the carburetor is associated. When used in an automobile the dial 88 and control knob 84 may be on the dashboard. Rotating the knob 84 rotates member 60, and consequently regulates the opening at 70 to thereby determine the engine's idling speed.

Member 54 is provided with lever 90 fixedly secured thereto as at 92, said lever being suitably connected as at 94 to the accelerator (not shown). Inasmuch as members 54 of injection devices 48 and 50 are fixed to sleeve 40 only one lever 90 need be connected to the accelerator, though levers 90 may be provided for both devices 48 and 50 to accommodate right or left handed disposition of carburetors on engines.

An inner third injection member 96 is disposed in the bore of member 60, said member comprising a tubular portion 98 having an externally and internally threaded end, adapted to be closed by plug 100, or connected to a source of pressure

supply as to a source of compressed air. Portion 98 is provided with a slidable spring seat 102, adjusted by wall 104 of nut 106 provided on the threaded end of member 60. Portion 98 is enlarged to provide a spring seat 108, spring 110 being disposed between seats 102 and 108 urging the tapered outer portion 112 into engagement with the complementarily tapered inner portion 114 of member 60, tapered portion 112 terminating in an end portion 116 fitting within the bore of member 60.

Lever 118 is fixedly connected at 120 to member 96 and is connected through suitable mechanism 122 to knob 124, whereby rotation of knob 124 rotates member 96. Knob 124 is provided with pointer 126 adapted to be moved over calibrated dial 128 to the selected setting. By this means the supply of fuel may be regulated from fully closed to fully opened.

Member 60 is provided with a manifold 130 connected through piping 132 to a suitable source of fuel supply and the port 134 in member 60 is adapted to form a valve with port 136 in member 96 to regulate the amount of fuel supplied from piping 132 to opening 70. This setting then effects a governing action, which however can be regulated by knob 124 by the engine operator, as for example, it may be regulated from the dashboard of a motor car. The ports 134 and 136 forming valves are preferably V-shaped (though other shapes may be used) to facilitate regulation and self-cleaning.

It will be noted that injection devices 48 and 50 are so arranged (Figure 2) that the operation 35 is the same, i. e., upon movement of the accelerator to rotate members 54, ports 72 open together; though of course they may be arranged to operate in a reverse direction should that be desired. It is contemplated that injection device 40 48 may be operated with device 50 or one may be used alone, or one may be used serially or in timed relation to the other.

In the modification shown in Figure 6 member 54 is provided mounted in closure 36 (and 38), said member 54 having end 52 provided with opening or port 72 cooperating with port 138 (similar to port 70) disposed in the tapered nozzle end 140 of member 142. Nozzle end 140 fits into a complementarily tapered portion in end 52, and is held therein by spring 144 disposed between the fixed spring seat 146 and slidable spring seat 148. Seat 148 is adjustably held by the end wall 150 of nut 152.

Instead of member 96 (Figures 3 and 6) interfitting in member 142, it interfits in the complementary bore of third inner injection member 154. Member 154 has a tapered end 156 disposed in contacting relation to the inner nozzle end 140 and is provided with a port 158 which will function as port 136 (Figures 7, 8 and 9) being a governor.

Member 154 is provided with fixed spring seat 160, and movable spring seat 162, adjustably held by end wall 164 of nut 166 provided on the threaded end of member 142. In this case member 154 has the manifold 168 (similar to manifold 130) and a port (not shown) similar to port 134, acting as a valve with substantially V-shaped port 136. Member 96 is held in operative position by spring 110 disposed between seats 108 and 102, seat 102 being adjustably held by nut 170 provided on the threaded end of member 154, and as before, end 116 extends into the bore of member 154.

The bore of member 96 is adapted to be con-

nected to a source of air pressure supply and lever 118 secured to member 96 as at 120 is connected to knob 124 (Figure 1) convenient to the operator. A lever 172 is secured as at 174 to member 154 and to a knob (not shown) of a dial similar to dial 88. Lever 78 is connected to member 142 and to the knob 84 of dial 88 (Figure 1). Lever 90 is connected as at 92 to member 54 and to the accelerator.

In the operation of the devices shown in Figures 1 to 9, inclusive, assuming a pair of injection devices are used, knob 84 is regulated to rotate member 60 (or member 142) to such a position that ports 70 and 72 are slightly open for idling, at which time port 42 is but slightly open for admission of air. When the desired idling position (air-fuel ratio) is attained knob 84 is rendered inoperative and remains so unless it is necessary to change it to effect a different idling action.

Levers 172 or 118 may then be moved (from their respective control knobs adjacent the operator) to regulate the amount of fuel possible to supply at full throttle. In other words levers 172 or 118 may be used as governors, which however can be changed at will by the operator if they may be operated by him while the engine is running. That is, in the case of an automobile driver, if the governing controls are near him as on the dashboard he can change the governor at his election. The difference between the devices shown in Figures 3 and 6 is that in Figure 3 lever 118 acts as a governor and in Figure 6 lever 172 acts as a governor. In Figure 6, lever 118 acts to control the port 136 and thus control fuel supply from manifold 168 to port 139 where its flow is governed to ports 72 and 138.

Operation of the accelerator rotates member 154 and sleeve 40 opening ports 70—72 and 138—72 and at the same time opening port 42 to supply more air to the increased fuel supply. Operation of the accelerator operates the fuel ports and air and mixture ports synchronously and simultaneously but the shape of the fuel ports is so chosen, i. e., are of unmatching shape (not of the same geometrical form) and so movable with respect to each other that amounts of fuel are disproportionately supplied to the changing amounts of air being supplied that the chosen air-fuel ratio is maintained throughout the entire throttle range. The air port 42 being of a different geometrical form from nozzle ports may also serve to insure the maintenance of the desired air-fuel ratio.

The opening of the fuel supplying ports of the device illustrated in Figure 6 is illustrated in Figures 7, 8 and 9. When idling ports 70 and 72 are just open, and member 116 (96) may be rotated to its governing position, for example it may be rotated from its position shown in Figure 7 to the maximum supply position shown in Figures 8 and 9. If then member 54 is rotated by the accelerator to its maximum position fully opening ports 70—72 such movement then fully opens port 42 permitting the maximum fuel supply to the maximum air supply. Release of the accelerator (to decelerate) operates the ports oppositely to return the ports toward a position where the selected amount of idling fuel is supplied to the minimum amount of air in the mixing chamber.

When the device shown in Figure 6 is used or where member 96 is connected to a source of air pressure supply (Figure 3) different regulation is necessary as the pressure at the nozzle ends is

greater than when an ordinary fuel pump with engine suction is depended upon.

As before mentioned the injection devices 48 and 50 may be used simultaneously to supply different fuels to be mixed. Or a valve may cut out one device or render it operative and inoperative at selected times.

In Figures 10 to 12 are shown different arrangements of injection devices for different fuels which can be readily utilized in the assembly shown in Figure 1 using either the injection devices of Figure 3 or 6. These can be simultaneously operated or utilized in another sequence.

In Figure 13, the injection device 178, similar to that of Figure 3 or 6, is connected to a main source of fuel supply 180 and controlled, as above described, being supplied by fuel pump 182. Said device discharges into the mixing chamber 184 (similar to chamber 46). Another injection device 186, of similar construction, discharges into the mixing chamber and this device is supplied by fuel through pump 188. This pump 188 is adapted to be connected to the outlet side of valve 190, said valve having a plurality of inlets connected to a plurality of sources of supply 192, 194 and 196. The outlets of tanks 192, 194 and 196 are provided with controllable devices which allow different percentages of fuels to be conducted to valve 190. The valve may be operated to connect any one or any combination of sources to said pump 188, so a wide selection of mixtures may be supplied to mixing chamber 184. Otherwise the operation of the devices shown in Figures 10 to 13 inclusive, is similar to that already described.

It is to be understood that this application is not to be limited by the exact embodiments of the device shown, which are merely by way of illustration and not limitation as various and other forms of the device will, of course, be apparent to those skilled in the art without departing from the spirit of the invention or the scope of the claims.

I claim:

1. In fuel metering mechanism, the combination of a casing having an outlet adapted to be connected to the inlet of an internal combustion engine, said casing having an air inlet, a rotary valve disposed in said casing and having ports for controlling the air inlet and said first named outlet, said casing and rotary valve forming a mixing chamber in said casing, injection mechanism extending into said mixing chamber, said injection mechanism comprising an outer injection member fixed to said rotary valve and provided with a nozzle end extending into the mixing chamber and provided with a nozzle outlet, a second injection member rotatably mounted in said outer injection member and having a nozzle end having a nozzle outlet adapted to be moved with respect to said first named nozzle outlet to regulate the flow to said mixing chamber, a third injection member rotatably mounted in said second injection member and provided with a nozzle end extending into the nozzle end of said second injection member, said nozzle end of said third injection member having a port adapted to be regulated with respect to said last named outlets, a fourth injection member extending into said third injection member and adapted to be connected to a source of pressure supply whereby pressure may be supplied to said nozzle ends, said third and fourth injection members having ports, the port of said third in-

jection member being connected to a source of fuel supply, said fourth injection member being movable when the ports of said third and fourth injection members form a valve to regulate fuel supply from said source to said nozzle ends, and means for relatively moving said injection members with respect to each other, movement of certain of said injection members toward fully open position being substantially simultaneous with movement of the rotary valve toward the fully open position of the air inlet.

2. In fuel metering mechanism, the combination of a casing having an outlet adapted to be connected to the inlet of an internal combustion engine, said casing having an air inlet, a rotary valve disposed in said casing and having ports for controlling the air inlet and said first named outlet, said casing and rotary valve forming a mixing chamber in said casing, injection mechanism extending into said mixing chamber, said injection mechanism comprising an outer injection member fixed to said rotary valve and provided with a nozzle end extending into the mixing chamber and provided with a nozzle outlet, a second injection member rotatably mounted in said outer injection member and having a nozzle end having a nozzle outlet adapted to be moved with respect to said first named nozzle outlet to regulate the flow to said mixing chamber, a third injection member extending into said second injection member and adapted to be connected to a source of pressure supply whereby pressure may be supplied to said nozzle ends, said second and third injection members having ports, the port of the second injection member being connected to a source of fuel supply, said third injection member being movable when the ports of said second and third injection members form a valve to regulate fuel supply from said source to said nozzle ends, and means for relatively moving said injection members with respect to each other, movement of certain of said injection members toward fully open position being substantially simultaneous with movement of the rotary valve toward the fully open position of the air inlet.

3. In fuel metering mechanism, the combination of a casing having an outlet adapted to be connected to the inlet of an internal combustion engine, said casing having an air inlet, a rotary valve disposed in said casing and having ports for controlling the air inlet and said first named outlet, said casing and rotary valve forming a mixing chamber in said casing, spaced injector mechanisms extending into said mixing chamber, each injection mechanism comprising an outer injection member fixed to said rotary valve and provided with a nozzle end extending into the mixing chamber and provided with a nozzle outlet, a second injection member rotatably mounted in said outer injection member and having a nozzle end having a nozzle outlet adapted to be moved with respect to said first named nozzle outlet to regulate the flow to said mixing chamber, a third injection member rotatably mounted in said second injection member and provided with a nozzle end extending into the nozzle end of said second injection member, said nozzle end of said third injection member having a port adapted to be regulated with respect to said last named outlets, a fourth injection member extending into said third injection member and adapted to be connected to a source of pressure supply whereby pressure may be supplied to said nozzle ends, said third and fourth injection mem-

bers having ports, the port of said third injection member being connected to a source of fuel supply, said fourth injection member being movable when the ports of said third and fourth injection members form a valve to regulate fuel supply from said source to said nozzle ends, and means for relatively moving said injection members with respect to each other, movement of certain of said injection members toward fully open position being substantially simultaneous with movement of the rotary valve toward the fully open position of the air inlet.

4. In fuel metering mechanism, the combination of a casing having an outlet adapted to be connected to the inlet of an internal combustion engine, said casing having an air inlet, a rotary valve disposed in said casing and having ports for controlling the air inlet and said first named outlet, said casing and rotary valve forming a mixing chamber in said casing, spaced injector mechanisms extending into said mixing chamber, each injector mechanism comprising an outer injection member rotatable with said rotary valve and provided with a nozzle end extending into the mixing chamber and provided with a nozzle outlet, a second injection member rotatably mounted in said outer injection member and having a nozzle outlet adapted to be moved with respect to said first named nozzle outlet to regulate the flow to said mixing chamber, a third injection member extending into said second injection member and adapted to be connected to a source of pressure supply whereby pressure may be supplied to said nozzle ends, said second and third injection members having ports, the port of the second injection member being connected to a source of fuel supply, said third injection member being movable when the ports of said second and third injection members form a valve to regulate fuel supply from said source to said nozzle ends, and means for relatively moving said injection members with respect to each other, movement of certain of said injection members toward fully open position being substantially simultaneous with movement of the rotary valve toward the fully open position of the air inlet.

5. Injection mechanism comprising an outer injection member having a nozzle end provided with a nozzle outlet, a second injection member rotatably mounted in said outer injection member and having a nozzle end having a nozzle outlet adapted to be moved with respect to said first named nozzle outlet to regulate the flow through the nozzle outlets, a third injection member rotatably mounted in said second injection member and provided with a nozzle end extending into the nozzle end of said second injection member, said nozzle end of said third injection member having a port adapted to be regulated with respect to said last named outlets, a fourth injection member extending into said third injection member and adapted to be connected to a source of pressure supply whereby pressure may be supplied to said nozzle ends, said third and fourth injection members having ports, the port of said third injection member being connected to a source of fuel supply, said fourth injection member being movable when the ports of said third and fourth injection members form a valve to regulate fuel supply from said source to said nozzle ends, and means for relatively moving said injection members toward each other.

6. Injection mechanism comprising an outer injection member having a nozzle end provided

with a nozzle outlet, a second injection member rotatably mounted in said outer injection member and having a nozzle end having a nozzle outlet adapted to be moved with respect to said first named nozzle outlet to regulate the flow from the nozzle end, a third injection member extending into said second injection member and adapted to be connected to a source of pressure supply whereby pressure may be supplied to said nozzle ends, said second and third injection members having ports, the port of the second injection member being connected to a source of fuel supply, said third injection member being movable when the ports of said second and third injection members form a valve to regulate fuel supply from said source to said nozzle ends, and means for relatively moving said injection members toward each other.

7. In fuel metering mechanism, the combination of a casing having an outlet adapted to be connected to the inlet of an internal combustion engine, said casing having an air inlet, a rotary valve disposed in said casing and having ports for controlling the air inlet and said first named outlet, said casing and rotary valve forming a mixing chamber in said casing, injection mechanism extending into said mixing chamber, said injection mechanism comprising an outer injection member fixed to said rotary valve and provided with a nozzle end extending into the mixing chamber and provided with a nozzle outlet, a second injection member rotatably mounted in said outer injection member and having a nozzle end having a nozzle outlet adapted to be moved with respect to said first named nozzle outlet to regulate the flow to said combustion chamber, a third injection member extending into said second injection member, said second and third injection members being held in assembled relation with said first injection member and with themselves by resilient means adjustably secured to said second and third injection members respectively, said second and third injection members having ports, the port of the second injection member being connected to a source of fuel supply, said third injection member being movable when the ports of said second and third injection members form a valve to regulate fuel supply from said source to said nozzle ends, and means for relatively moving said injection members with respect to each other, movement of certain of said injection members toward fully open position being substantially simultaneous with movement of the rotary valve toward the fully open position of the air inlet.

8. In fuel metering mechanism for an internal combustion engine, the combination of a casing having an outlet adapted to be connected to the fuel inlet of an internal combustion engine, said casing having an air inlet, the casing having an axial cylindrical bore, a cylindrical valve member rotatably mounted in said bore and provided with ports for controlling flow through said casing outlet and inlet, said rotary valve and casing forming a mixing chamber, closures for the ends of said casing, one of said closures being rotatable and connected to said valve member, an injection device disposed on the axis of said valve member and extending into the mixing chamber, said injection device comprising an outer injection member fixed to said rotatable closure and having its axis disposed on the axis of said valve member, the nozzle end of said injection member being disposed in said mixing

75

chamber, a second injection member rotatably mounted in said outer injection member and having a nozzle end extending into the nozzle end of said outer injection member, said nozzle ends having fuel ports for controlling the passage of fuel to said mixing chamber, rotation of the outer injection member rotating the valve member to vary the casing inlet and outlet and also rotate the port of the outer injection member with respect to the port of the inner injection member to vary the supply of fuel to said mixing chamber, and throttle means for simultaneously rotating the outer injection member and said valve member, rotation of the outer injection member and said valve member serving to regulate the fuel ports with respect to the casing inlet and outlet to maintain a selected air-fuel ratio during the entire operation of the throttle means.

9. In fuel metering mechanism for an internal combustion engine, the combination of a casing having an outlet adapted to be connected to the fuel inlet of an internal combustion engine, said casing having an air inlet, the casing having an axial cylindrical bore, a cylindrical valve member rotatably mounted in said bore and provided with ports for controlling flow through said casing outlet and inlet, said rotary valve and casing forming a mixing chamber, closures for the ends of said casing, one of said closures being rotatable and connected to said valve member, an injection device disposed on the axis of said valve member and extending into the mixing chamber, said injection device comprising an outer injection member fixed to said rotatable closure and having its axis disposed on the axis of said valve member, the nozzle end of said injection member being disposed in said mixing chamber, a second injection member rotatably mounted in said outer injection member and having a nozzle end extending into the nozzle end of said outer named injection member, said nozzle ends having fuel ports for controlling the passage of fuel to said mixing chamber, rotation of the outer injection member rotating the valve member to vary the casing inlet and outlet and also rotate the port of the outer injection member with respect to the port of the inner injection member to vary the supply of fuel to said mixing chamber, throttle means for simultaneously rotating the outer injection member and said valve member, rotation of the outer injection member and said valve member serving to regulate the fuel ports with respect to the casing inlet and outlet to maintain a selected air-fuel ratio during the entire operation of the throttle means, and means for rotating the inner injection member in any throttle position for adjusting the fuel ports to selectively change the air-fuel ratio for any opening of the casing inlet and outlet.

10. In fuel metering mechanism for an internal combustion engine, the combination of a casing having an outlet adapted to be connected to the fuel inlet of an internal combustion engine, said casing having an air inlet, the casing having an axial cylindrical bore, a cylindrical valve member rotatably mounted in said bore and provided with ports for controlling flow through said casing outlet and inlet, said rotary valve and casing forming a mixing chamber, closures for the ends of said casing, said closures being rotatable and connected to said valve member, injection devices disposed on the axis of said valve member and extending into the

mixing chamber, each injection device comprising an outer injection member fixed to said closures and having its axis disposed on the axis of said valve member, the nozzle end of each injection member being disposed in said mixing chamber and each extending toward the other, a second injection member rotatably mounted in each outer injection member and having a nozzle end extending into the nozzle end of the associated outer injection member, each nozzle end of each injection member having a fuel port for controlling the passage of fuel to said mixing chamber, rotation of each outer injection member rotating the valve member to vary the casing inlet and outlet and also rotate the port of each outer injection member with respect to the port of the associated inner injection member to vary the supply of fuel to said mixing chamber and throttle means for simultaneously rotating each outer injection member and said valve member, rotation of each outer injection member and said valve member serving to regulate the fuel ports with respect to the casing inlet and outlet to maintain a selected air fuel ratio during the entire operation of the throttle means.

11. In fuel metering mechanism for an internal combustion engine, the combination of a casing having an outlet adapted to be connected to the fuel inlet of an internal combustion engine, said casing having an air inlet, the casing having an axial cylindrical bore, a cylindrical valve member rotatably mounted in said bore and provided with ports for controlling flow through said casing outlet and inlet, said rotary valve and casing forming a mixing chamber, closures for the ends of said casing, said closures being rotatable and connected to said valve member, injection devices disposed on the axis of said valve member and extending into the mixing chamber, each injection device comprising an outer injection member fixed to said closures and having its axis disposed on the axis of said valve member, the nozzle end of each injection member being disposed in said mixing chamber and each extending toward the other, a second injection member rotatably mounted in each outer injection member and having a nozzle end extending into the nozzle end of the associated outer injection member, each nozzle end of each injection member having a fuel port for controlling the passage of fuel to said mixing chamber, rotation of each outer injection member rotating the valve member to vary the casing inlet and outlet and also rotate the port of each outer injection member with respect to the port of the associated inner injection member to vary the supply of fuel to said mixing chamber and throttle means for simultaneously rotating each outer injection member and said valve member, rotation of each outer injection member and said valve member serving to regulate the fuel ports with respect to the casing inlet and outlet to maintain a selected air fuel ratio during the entire operation of the throttle means, and means for rotating each inner injection member for adjusting the fuel ports to selectively change the air fuel ratio for any opening of the casing inlet and outlet.

12. In fuel metering mechanism for an internal combustion engine, the combination of a casing having an outlet adapted to be connected to the fuel inlet of an internal combustion engine, said casing having an air inlet, the casing having an axial cylindrical bore, a cylindrical valve member rotatably mounted in said bore and pro-

vided with ports for controlling flow through said outlet and inlet, said rotary valve and casing forming a mixing chamber, closures for the ends of said casing, one of said closures being rotatable and connected to said valve member, an injection device disposed on the axis of said valve member and extending into the mixing chamber, said injection device comprising an outer injection member fixed to said rotatable closure and having its axis disposed on the axis of said valve member, the nozzle end of said injection member being disposed in said mixing chamber, a second injection member rotatably mounted in said outer injection member and having a nozzle end extending into and closing the nozzle end of said outer injection member, said nozzle ends having ports for controlling the passage of fuel to said mixing chamber, said last named ports being of different geometrical shapes, rotation of the outer injection member rotating the valve member to vary the inlet and outlet and also rotate the port of the outer injection member with respect to the port of the inner injection member to vary the supply of fuel to said mixing chamber, and throttle means for simultaneously rotating the outer injection member and said valve member, rotation of the outer injection member and said valve member serving to regulate the fuel ports with respect to the inlet and outlet to maintain a selected air-fuel ratio during the entire operation of the throttle means.

13. In fuel metering mechanism for an internal combustion engine, the combination of a casing having an outlet adapted to be connected to the fuel inlet of an internal combustion engine, said casing having an air inlet, the casing having an axial cylindrical bore, a cylindrical valve member rotatably mounted in said bore and provided with ports for controlling flow through said casing outlet and inlet, said rotary valve and casing forming a mixing chamber, closures for the ends of said casing, one of said closures being rotatable and connected to said valve member, an injection device disposed on the axis of said valve member and extending into the mixing chamber, said injection device comprising an outer injection member fixed to said rotatable closure and having its axis disposed on the axis of said valve member, the nozzle end of said injection member being disposed in said mixing chamber, a second injection member rotatably mounted in said outer injection member and having a nozzle end extending into the nozzle end of said outer named injection member, said nozzle ends having fuel ports for controlling the passage of fuel to said mixing chamber, rotation of the outer injection member rotating the valve member to vary the casing inlet and outlet and also rotate the port of the outer injection member with respect to the port of the inner injection member to vary the supply of fuel to said mixing chamber, the shape of at least one of said fuel ports being of different geometrical shape than that of said casing inlet, and throttle means for simultaneously rotating the outer injection member and said valve member, rotation of the outer injection member and said valve member serving to regulate the fuel ports with respect to the casing inlet and outlet to maintain a selected air-fuel ratio during the entire operation of the throttle means.

14. In fuel metering mechanism for an internal combustion engine, the combination of a casing having an outlet adapted to be connected

to the fuel inlet of an internal combustion engine, said casing having an air inlet, a valve member rotatably mounted in said casing for controlling flow through said casing outlet and inlet, said casing having a mixing chamber therein, an injection device extending into the mixing chamber, said injection device comprising an outer injection member rotatable in said mixing chamber, the nozzle end of said injection member being disposed in said mixing chamber, a second injection member rotatably mounted in said outer injection member and having a nozzle end extending into the nozzle end of said outer named injection member, said nozzle ends having fuel ports for controlling the passage of fuel to said mixing chamber, a connection between said valve member and outer injection member, rotation of the outer injection member rotating the valve member to vary the casing inlet and outlet and also rotate the port of the outer injection member with respect to the port of the inner injection member to vary the supply of fuel to said mixing chamber, and throttle means for simultaneously rotating the outer injection member and said valve member, rotation of the outer injection member and said valve member serving to regulate the fuel ports with respect to the casing inlet and outlet to maintain a selected air-fuel ratio during the entire operation of the throttle means.

15. In fuel metering mechanism for an internal combustion engine, the combination of a casing having an outlet adapted to be connected to the fuel inlet of an internal combustion engine, said casing having an air inlet, the casing having an axial cylindrical bore, a cylindrical valve member rotatably mounted in said bore and provided with ports for controlling flow through said casing outlet and inlet, whereby one of said rotary valve ports forms an air entrance with the casing inlet and the other rotary valve port forms a mixture exit with said casing outlet, said rotary valve and casing forming a mixing chamber, closures for the ends of said casing, one of said closures being rotatable and connected to said valve member, an injection device disposed on the axis of said valve member and extending into the mixing chamber, said injection device comprising an outer injection member fixed to said rotatable closure and having its axis disposed on the axis of said valve member, the nozzle end of said injection member being disposed in said mixing chamber, a second injection member rotatably mounted in said outer injection member and having a nozzle end extending into the nozzle end of said outer injection member, said nozzle ends having fuel ports for controlling the passage of fuel to said mixing chamber, rotation of the outer injection member rotating the valve member to vary the casing inlet and outlet and also rotate the port of the outer injection member with respect to the port of the inner injection member to vary the supply of fuel to said mixing chamber, the shape of at least one of said fuel ports being of different geometrical shape than that of the air entrance, and throttle means for simultaneously

rotating the outer injection member and said valve member, rotation of the outer injection member and said valve member serving to regulate the fuel ports with respect to the air entrance and valve exit to maintain a selected air-fuel ratio during the entire operation of the throttle means.

16. In fuel metering mechanism for an internal combustion engine, the combination of a casing having an outlet adapted to be connected to the fuel inlet of an internal combustion engine, said casing having an air inlet, a valve member rotatably mounted in said casing for controlling flow through said casing outlet and inlet, said casing having a mixing chamber therein, movement of the valve member varying the air entrance and mixture exit to and from the mixing chamber, an injection device extending into the mixing chamber, said injection device comprising an outer injection member rotatable in said mixing chamber, the nozzle end of said injection member being disposed in said mixing chamber, a second injection member rotatably mounted in said outer injection member and having a nozzle end extending into the nozzle end of said outer named injection member, said nozzle ends having fuel ports for controlling the passage of fuel to said mixing chamber, a connection between said valve member and outer injection member, rotation of the outer injection member rotating the valve member to vary the casing inlet and outlet and also rotate the port of the outer injection member with respect to the port of the inner injection member to vary the supply of fuel to said mixing chamber, the shape of at least one of said fuel ports being of different geometrical shape than that of the air entrance, and throttle means for simultaneously rotating the outer injection member and said valve member, rotation of the outer injection member and said valve member serving to regulate the fuel ports with respect to the air entrance and valve exit to maintain a selected air-fuel ratio during the entire operation of the throttle means.

EUGENE RIVOCHE.
